Attorney.

UNITED STATES PATENT OFFICE

REUBEN HITCHCOCK, OF CLEVELAND, OHIO, ASSIGNOR TO THE CLEVELAND FOLDING MACHINE COMPANY, OF CLEVELAND, OHIO, A CORPORATION OF OHIO.

KNURLING.

Application filed November 3, 1923. Serial No. 672,691.

My invention relates to improvements in knurling and knurled rolls such as are employed in paper-handling machines; the object of my invention being the more rapid and efficient production of rolls of this type, or of allied articles, which will render better and longer service than those of the prior art.

Previously it has been considered necessary to maintain the acute knurled edges or "lands" upon such rolls as sharp as is practicable to insure the most efficient handling of paper stock. Moreover, these knurled lands, as fabricated, invariably were found to be of unequal height upon opposite sides of a longitudinal depression or cup, so that only one of each pair, when slightly dressed to bring the roll to approximately a uniform diameter, contributed to the effective or operative face of the roll. These sharp edges scored or marked the paper as it was passed between such paired rolls, while the wearing qualities of the knurled rolls were far from satisfactory.

I may explain that the land of the knurled rolls, or of other articles, are minute longitudinal fins or edges irregular in continuity and acute as to cross section, that are produced on either side of the entering teeth of the knurls during their spiral travel longitudinally of the work or blank roll. These are separated by a relatively shallow longitudinal cup or depression.

Accordingly, it has been my endeavor to discover a method for successfully producing a knurled roll with the lands sufficiently elevated to permit of dressing or grinding both of them, while retaining a sufficiently deep cup or depression therebetween to insure an effective operating face for the roll and one that will stand up under continued use.

The features of my improvement may best be explained in connection with the accompanying drawings illustrating means for practicing my invention and the knurled rolls produced thereby:

Figure 1 of said drawings illustrating two of such paired rolls in plan view, but centrally broken away, and with their spacing or separation greatly exaggerated for the purposes of illustration,

Figure 2 of the drawings shows a cross section through the rolls on line 2—2, Fig. 1,

Fig. 3 is a greatly enlarged fragmentary section of a roll milled in the usual manner,

Fig. 4 is a similar view illustrating a fragment of the operative face of the roll fabricated in accordance with my invention,

Fig. 5 is another greatly enlarged fragmentary section, somewhat diagrammatic in character, illustrating two co-acting rolls of the art with a sheet of paper engaged thereby,

Fig. 6 is a similar view of two co-acting rolls made in accordance with my instant improvements,

Fig. 7 is a transverse fragmentary section on line 7—7, Fig. 3, illustrating the partially dressed and undressed lands,

Fig. 8 is another transverse section on line 8—8, Fig. 4, illustrating the completely dressed land,

Fig. 9 is a plan view of a lathe broken away at its ends, wherein my improved method may advantageously be practiced,

Fig. 10 is a side elevation thereof also broken away,

Fig. 11 is a transverse section on line 11—11, Fig. 9, and

Fig. 12 is an enlarged cross sectional view of the knurls and knurled roll on line 12—12, Fig. 10.

Throughout the several figures of said drawings I have employed the same character of reference to indicate similar parts or members.

Knurled rolls for paper-handling machines are well known in the art, comprising the longitudinally knurled and dressed sections *a* spaced slightly apart by the terminal bands *b* of hardened steel and from .00025" to .0005" larger diameter than the operative portions *a* of said rolls. It will be understood that the spacing shown is exaggerated only for the purpose of illustration, since it would be inoperative for handling paper.

These rolls, as previously fabricated in the art, have comprised lands *c*, *c'* of material inequality in height, separated by the longitudinal cup or depression *c''*. It was deemed practically necessary to maintain the lands as sharp or acute as possible, while it is essential that the cup or depression shall remain of appreciable depth. Accordingly, the more elevated lands *c* alone

were ground or dressed to complete the operative face of the roll; their appearance as greatly magnified being shown in Fig. 7, thus presenting slight irregularity of line 5 as compared with the jagged line of the shorter land thrown up by the knurls.

It will be appreciated that while the lands *c* of these rolls presented relatively sharp edges throughout for contacting with and 10 advancing the paper, their wearing qualities were not satisfactory, while these sharp and slightly irregular edges were found to score or mark the paper or signatures as they were passed therebetween. The action 15 of such opposing paired rolls of the prior art upon an interposed sheet of paper *d* is typically shown in Fig. 5 with the higher sets of lands *c* alone in contact with the paper. Thus the wear was confined to one 20 set of lands only.

Having these considerations and disadvantages in mind, it was my object so to improve the method of fabricating such rolls, or similar articles, and to improve the rolls 25 themselves, that their wearing qualities, action and efficiency might be materially augmented. To this end, I have perfected a method or methods of producing rolls with lands more nearly equal in height and much 30 more rapidly than were the rolls as previously knurled. One mode of improving the knurling in this respect is to interspace the lands with relatively deeper and wider cups. Thus, upon referring to Figs. 4, 6 35 and 8, it will be noted that the lands *e*, *e'* are more nearly equal in height, while the intervening longitudinal depressions or cups *d''* are more accentuated than were obtained in the prior art.

Moreover, I have found that by knurling with a plurality of knurls of slightly different diameters, the knurl with the least diameter leading or preceding in the operation, the fabrication of my improved rolls 40 may be effected approximately in one-third the time required in following the accepted practice employing commonly merely two opposing knurls. Thus the knurl of larger diameter, tracking the slightly smaller knurl 45 in advance thereof, will bite deeper into the work and more rapidly, while facilitating the fabrication of lands more nearly equal in height, as previously explained.

Referring now to Figs. 9 to 12, the work 50 or roll *f* is shown positioned in a lathe having the usual travelling support *g* actuated by the screw *g'* for effecting its travel longitudinally of the lathe bed *h*. Two sets of 55 opposing knurls *i*, *i'* and *j*, *j'* are shown in operative position upon said support and in engagement with the work or roll; having been advanced approximately one-half the length of the roll in their spiral course along its operative face. The usual knurled member *f'* is provided at the extreme right of the

roll for effecting the alinement or register of the opposing sets of knurls previous to their engagement with the work *f*. The travel of the support and co-acting knurls is toward the left as indicated by the arrow, and the roll, under high magnification, will appear approximately as shown in Fig. 4 with the lands acutely pointed in accordance with the dotted lines. This mode of knurling permits the lands to be dressed or 70 ground, as shown, so that they present straight edges, respectively, and the roll may be made of uniform diameter throughout its operative face.

In Fig. 12 I have illustrated, although in 80 exaggerated form, of course, the provision of two opposing paired knurls, *i*, *i'*, and *j*, *j'*; the pair in advance being of less diameter, say ".005" as compared with the following pair. This arrangement materially improves 85 the fabrication of the rolls and shortens the time required by one-half to two-thirds over the prior practice.

Comparing the showing of Figs. 5 and 6 to illustrate the action of the paired rolls 90 of the prior art and of my present improvement, respectively, it is seen that merely the relatively high, sharp lands *c*, *c* of each pair of rolls actually engage the sheet of paper *d*, which commonly is scored or marked 95 thereby. On the other hand, double the number of lands *e*, *e'* are in engagement with the sheet of paper *d* in Fig. 6, which illustrates the blunted ground lands of the paired rolls constructed in accordance with 100 my invention. These do not score or mark the paper and are even more effective in their operation in paper-handling mechanism than were the sharp paired rolls of the prior art. It is further to be observed that the 105 theoretical positioning of the opposing lands and cups is more effective through insuring a better grip upon the advancing sheet or signature than is obtainable with the arrangement of rolls in Fig. 5, while the wear upon the operative faces of the rolls is much 110 more advantageously distributed in the knurled rolls of the instant improvement.

Having now described the preferred 115 method for practicing my invention and for producing the new and novel article of manufacture above described, I claim as new, and desire to secure by Letters Patent, together with such modifications as may be made by those ordinarily skilled in the art, 120 the following:

1. The herein described method of knurling, which consists in subjecting the work to the action of a rotatable knurl, mounting a second knurl to rotate co-axially with the first knurl and causing said second knurl to deepen the impression made by the first knurl upon the work, substantially as set forth.

2. The herein described method of knurl-

ing, which consists in subjecting the work to the action of a plurality of knurls in succession and of varying diameters mounting the successive knurls to rotate co-axially and causing the knurl of greater diameter to deepen the impressions made by the smaller knurl, substantially as set forth.

3. The herein described method of knurling, which consists in subjecting the work to the action of a plurality of opposing sets of leading and following knurls, mounting the following knurls to rotate co-axially with the leading knurls and causing said following knurls to deepen the impressions made by the leading knurls, substantially as set forth.

4. The herein described method of knurling rolls, which consists in subjecting the work or blank roll to the action of paired opposing knurls and to the action of paired opposing knurls positioned to bite more

deeply into the work than are the first pair of knurls, substantially as set forth.

5. The herein described method of knurling, which consists in subjecting the work to the action of opposing paired knurls and to a second set of opposing paired knurls in closer proximity than are the first set with respect to their operative faces, substantially as set forth.

6. The herein described method of knurling, which consists in partially knurling the work with one set of knurls, mounting a second set of knurls of larger diameter to rotate co-axially with the first set of knurls and causing said second set of knurls to deepen the impressions made by the first set of knurls, substantially as set forth.

In testimony whereof I do now affix my signature.

REUBEN HITCHCOCK.
